UNITED STATES PATENT OFFICE

165,899

BABY'S SEAT

Stephen H. Bishop, Waban, Mass.

Application October 3, 1950, Serial No. 12,440

Term of patent 14 years

(Cl. D15—8)

To all whom it may concern:

Be it known that I, Stephen H. Bishop, a citizen of the United States, residing at Waban, in the county of Middlesex and Commonwealth of Massachusetts, have invented a new, original, and ornamental Design for a Baby's Seat, of which the following is a specification, reference being had to the accompanying drawing, forming part thereof.

I claim:

The ornamental design for a baby's seat, as shown.

STEPHEN H. BISHOP.
